UNITED STATES PATENT OFFICE.

CARL BECKMANN, OF BROOKLYN, NEW YORK.

WRAPPING-MACHINE.

1,234,605.

Specification of Letters Patent. Patented July 24, 1917.

Application filed May 6, 1916. Serial No. 95,819.

To all whom it may concern:

Be it known that I, CARL BECKMANN, a citizen of the United States, and a resident of the city of New York, borough of Brooklyn, in the county of Kings and State of New York, have invented a new and Improved Wrapping-Machine, of which the following is a full, clear, and exact description.

10 This invention relates to a machine construction for automatic cartoning machines, bottle wrapping machines, package making machines, etc., and it has to deal more particularly with means for automatically feeding the cartons, bottles, packages or the like to and from the various mechanisms which go to make up the machine.

The invention has for its general objects to provide a novel mechanism whereby the 20 articles are fed successively through the machine in an expeditious and effective manner, the invention being particularly adapted for that type of machine which employs a plurality of rotary or traveling carriers in which the filling, closing and sealing of the cartons takes place successively, the mechanism having simultaneously acting parts whereby an empty carton is fed to one carrier, while a filled carton is transferred from 25 one carrier to the other, and a filled and sealed carton discharged from the final carrier; and the same is true whether the carriers are used for wrapping bottles or other articles or the making of packages.

30 A more specific object of the invention is the provision of a mechanism embodying simultaneously acting feeding, transferring and delivering means mounted on a common element which is supported by parallel links 35 and receives reciprocatory motion by movement of the links, whereby the feeding to one part of a carrier, transferring from another part of such carrier to a second carrier, and delivering from such second carrier, can take place at one and the same time.

With such objects in view, and others which will appear as the description proceeds, the invention comprises various novel features of construction and arrangement of 40 parts which will be set forth with particularity in the following description and claims appended hereto.

In the accompanying drawings, which illustrate one embodiment of the invention and wherein similar characters of reference 55 indicate corresponding parts in all the views,

Figure 1 is a side view of the machine construction;

Fig. 2 is a plan view;

Fig. 3 is a sectional view on the line 3—3, 60 Fig. 1;

Figs. 4 and 5 are detail views showing the folding of the flaps of the carton incident to the transference of a carton from one carrier to the other; and 65

Figs. 6 to 9 inclusive are end views of the carton, showing the successive steps in the folding of the flaps.

Referring to the drawing, A and B designate two rotary carriers which are disposed 70 parallel to each other to rotate on horizontal axes, and these carriers are so designed as to enable the filling, closing and sealing of cartons, the filling taking place in the first carrier, partial closing taking place while passing from the first to the second carrier, and the final closing and sealing while discharging from the second carrier, but it is to be understood that these carriers may be designed for the wrapping or labeling of other 75 articles, or for the making of packages. 80

The empty cartons are supplied from a hopper C by an upsetting machine disclosed in a co-pending application filed by me. The cartons are supplied successively to a guideway D by a horizontal feeding bar 1 which causes the cartons to move step by step through the guideway D to the first carrier A. The carriers rotate step by step in timed relation to the reciprocation of the feeding 85 bar 1. The means for filling the cartons and pasting the flaps are not disclosed, as they are well known. The carton after being filled in the first carrier is transferred to the second carrier by transfer fingers 2 located 90 between the carriers, and finally the carton is discharged from the second carrier by discharging fingers 3, which cause the sealed cartons to move step by step through a guideway E at the delivery end of the machine. The feeding means 1, transferring means 2 and the delivering means 3 are carried by horizontal bars 4 at opposite sides of 95 the machine. These bars are supported on 100

the upper ends of vertical parallel links 5 pivoted at 6 on the base 7 of the machine. By supporting the feeding, transferring and delivering means in this manner they all 5 move to the right or left, simultaneously, and consequently there will be a simultaneous feeding of a carton to the carrier A, the transfer of a filled carton from the carrier A to the carrier B, and the delivery of the 10 sealed carton to the guideway E. In Fig. 2 an empty carton b is shown just in front of the feeding bar 1, while a filled but partially closed carton b' is shown just in front of the transfer fingers 2, and a sealed carton b² is 15 shown in front of the delivery fingers 3. When the links 4 are moved to their limit toward the left, the bar 1 and fingers 2 and 3 will be so positioned that an empty carton can be delivered upwardly from the upper 20 setting mechanism at c and a filled carton can move downwardly in front of the fingers 2 and a sealed carton move downwardly in front of the fingers 3, it being understood that the carriers rotate in a clockwise direction. The bars 4 can be reciprocated in any 25 suitable manner, as, for instance, by an eccentric rod 8 connected at 9 with the rear links 5, and receiving motion from an eccentric 10 which is driven by a transmission 30 11 from a motor 12.

The carriers in the present instance are shown as rotary drums having pockets on the periphery so designed that the cartons will be held with their length parallel with 35 the axis of rotation, so that the end flaps of the cartons will be in the best position for closing and sealing. Each pocket embodies a pair of plates 15 forming the side walls of the pockets, the pockets being open at the 40 ends, and in fact, the yielding walls 15 are in the form of jaws pivoted at 16 on the body of the carrier, whereby the jaws constitute a mouth into which a carton or other article can be inserted, and after the insertion 45 the article will be held by reason of the closing pressure exerted by the springs 17. The cartons enter the pockets radially and are pushed out radially, and being pushed out, only the frictional grip of the walls 15 50 need be overcome. When an empty carton is fed into the carrier A, all of the end flaps of the carton are open, as shown at the left end of Fig. 2 by the dotted lines. By the time the carrier A makes one-half revolution, 55 the carton after being filled reaches a point in front of the transfer fingers 2, but in moving down in front of these fingers, the flaps f engage stationary folding fingers 18 mounted on the top 19 of the machine frame, 60 and thereby the flaps f are folded upwardly, as in Figs. 4 and 6. As the carton is being transferred by the transfer members 2, folding levers 20 engage the flaps f' and fold the latter downwardly over the up-folded flaps f,

as shown in Figs. 5 and 7. The levers 20 are 65 fulcrumed at 21 on the bars 4, so that as the latter move to the right, the lower free ends 22 of the levers 20 will engage the stationary fingers 18 and thereby the upper ends of the levers 20 will have a downward as well 70 as a lateral movement to effect the folding down of the flaps f'. During this time the transfer fingers 2 move the carton from the carrier A into an alining pocket of the carrier B. At the ends of the pockets of the 75 carrier B are folding fingers 23 which fold on back flaps f² when the carton enters the pocket of the carrier B, this step being shown in Fig. 8. After the carton has been transferred to the carrier B it is progressively moved to a position in alinement with the discharge chute or guideway E, and when at this point the filled carton is discharged by the fingers 3. At some point in the travel of the carton to the point of discharge, paste-applying means (not shown) applies paste to the flap f³. This flap f³ is folded back by means of bars e at the sides of the discharge guideway E, and these bars are of sufficient length as to hold the flap firmly 80 while the paste sets and during the step-by-step movement of the filled cartons in the guideway E.

From the foregoing description taken in connection with the accompanying drawings, 95 the advantages of the construction and method of operation will be readily understood by those skilled in the art to which the invention appertains, and while I have described the principle of operation, together 100 with the machine which I now consider to be the best embodiment thereof, I desire to have it understood that the machine shown is merely illustrative and that such changes 105 may be made when desired as fall within the scope of the appended claims.

Having thus described my invention, I claim as new and desire to secure by Letters Patent:

1. A machine of the class described comprising a pair of rotary carriers, a feeder in front of the first carrier for feeding articles thereto, a transerrer between the carriers for transferring articles from the first to the second, a discharger behind the second carrier for discharging articles therefrom, supporting means for the feeder, transerrer and discharger, and means for actuating the supporting means.

2. A machine of the class described comprising a pair of carriers, a feeder for feeding articles to the first carrier, a transerrer for transferring articles from one carrier to the other, a discharger for discharging articles from the second carrier, a common support for the feeder, transerrer and discharger, and means for reciprocating the support, said support embodying parallel

links for causing rectilinear reciprocatory movement of the feeder, transerrer and discharger.

3. A machine construction embodying a 5 pair of carriers, a feeder for feeding articles successively to the first carrier, a transerrer for transferring articles from the first to the second carrier, a discharger for discharging

articles from the second carrier, a pair of reciprocatory bars supporting the feeder, 10 transerrer and discharger, parallel links extending transversely to the bars and pivotally connected therewith, and means for oscillating the links to reciprocate the bars.

CARL BECKMANN.
